GOLF PUTTER HEAD

Edward L. Cicero, 52-62 66th St.,
Maspeth, N.Y. 11378

Filed Oct. 27, 1970, Ser. No. 25,685

Term of patent 14 years

Int. Cl. D21—02

U.S. Cl. D34—5

FIG 1

FIG 3

FIG 2

FIG 4

FIG. 1 is a top plan view of a golf putter head showing my new design.

FIG. 2 is a view in side elevation, the front striking surface of which is to the left.

FIG. 3 is a front view.

FIG. 4 is a bottom plan view.

I claim:

The ornamental design for a golf putter head, as shown and described.
